SHOE

Charles B. Scoville, Jr., Carmel, Calif.

Application July 22, 1949, Serial No. 4,077

Term of patent 14 years

(Cl. D7—7)

To all whom it may concern:

Be it known that I, Charles B. Scoville, Jr., a citizen of the United States, residing at Carmel, in the county of Monterey and State of California, have invented a new, original, and ornamental Design for a Shoe, of which the following is a specification, reference being had to the accompanying drawing, forming a part thereof.

In the drawing:

Fig. 1 is a side view of a shoe, embodying my new design;

Fig. 2 is a plan view of the same; and

Fig. 3 is a front view of the same.

I claim:

The ornamental design for a shoe, substantially as shown.

CHARLES B. SCOVILLE, JR.
